ATTORNEYS.

UNITED STATES PATENT OFFICE.

EMORY QUIGLEY DARR, OF SHELBYVILLE, INDIANA.

BRIDLE-BLIND.

SPECIFICATION forming part of Letters Patent No. 328,657, dated October 20, 1885.

Application filed July 13, 1885. Serial No. 171,508. (No model.)

To all whom it may concern:

Be it known that I, EMORY Q. DARR, of 5
Shelbyville, in the county of Shelby and State
of Indiana, have invented a new and useful
Improvement in Bridle-Blinds, of which the
following is a full, clear, and exact description.

My invention relates to bridle-blinds, and
has for its object to facilitate their manufac-
ture and provide for a more secure and bet-
ter finished attachment of the winker-stays to
the blinds and of the blinds to the cheek-straps
of the bridle, and also to promote increased
durability of the blinds over those otherwise
constructed.

15 The invention consists in certain novel fea-
tures of construction and combinations of parts
of the blinds and in the mode of attaching
them to the bridle cheek-straps, all as herein-
after fully described and claimed.

20 Reference is to be had to the accompanying
drawings, forming a part of this specification,
in which similar letters of reference indicate
corresponding parts in all the figures.

Figure 1 is a perspective view of the upper
25 portion of a bridle with the blinds constructed
and attached in accordance with my invention.
Fig. 2 is an inner face view of one of the
blinds and a portion of the cheek-strap to
which it is attached with the inner cover or
30 facing of the blind partly broken away. Fig.
3 is a sectional plan view of the blind, taken
on the line *x x*, Fig. 2; and Fig. 4 is an outer
face view of a blind smaller in size and with
its outer cover or facing applied in a different
35 way and partly broken away.

Referring, first, to Figs. 1, 2, and 3, the letter
A indicates the blind or winker, which is at-
tached to the cheek-strap B, the opposite
cheek-straps being connected by a crown-strap,
40 C, to which one end of the winker-stay strap
D is buckled or attached in the usual way,
said winker-strap branching off into the straps
d d, which are attached at their lower ends to
the opposite blinds or winkers A A, and may
45 pass either inside or outside of the front strap,
E, of the bridle; or the winker-stay straps
may be attached to the strap E, instead of to
the strap C, if desired. Each blind A con-
sists of an outer facing, a, and an inner fac-
50 ing, a', both preferably made of leather, and
between these facings around the margin or top,
bottom, and outer edges of the blind and as close

as may be to the extreme edges of the blind is
placed a wire, F, which has formed in it by
suitable bends the loop G, which extends from 55
the edge of the blind a suitable distance to
have attached to it the end of the correspond-
ing winker-stay strap d. For a square or rect-
angular blind the loop G will extend from the
upper outward corner of the blind, as shown; 60
but for blinds of oval or other shape the mar-
ginal wire F may be bent at any required
place to project a loop, G, from the edge of
the blind at the most advantageous position
for attachment of the winker-stay, depending 65
on the shape of the blinds and the style of
bridle to which they are attached.

As best seen in Figs. 2 and 3, there is an
outer row of stitching, H, around the blind
uniting the facings a a' outside of the wire F, 70
and an inner row of stitching, I, uniting the
facings inside of the wire F, both of said rows
of stitching crossing the space between the
ends of the loop G, and closing the facings a
a' firmly together at this point. The wire F 75
thus is "pocketed" between the facings and
parallel rows of stitching H I, excepting the
projecting loop G, and cannot move out of
place, and forms an effective and light edge-
stiffener to the blind, while affording a means 80
of attachment for the winker-stay straps d d,
which is more substantial than that secured
by stitching the straps d d directly to the
blinds, and also insures for the blind a neater
and better finish, as the facings of the blind 85
are not bulged out, as they would be by the
attachment of the stay-straps d directly to
them by stitching in the usual way. The
space inclosed by the inner row of stitches at
I provides a pocket in which is placed the 90
metal stiffener-plate J, which thus is made
smaller than usual, and is separated from the
outer row or line, H, of stitches by the wire F;
hence the plate J will not cut its way through
the stitching at any point, and the durability 95
of the blind thereby is increased. The facings
a a' extend backward from the rear edge of
the stiffener-plate J, so as to lie between the
layers b b of the cheek-strap B, and a line of
stitches, K, is made through the blind-facings 100
a a' and the cheek-strap and across the back
ends of the wire F, whereupon said ends are
bent inward toward each other, as at f f, and
outside of the line K of stitches, and when

the extreme back row of stitches is made at L through the facings a a' and the cheek-strap the attachment of the blind to the bridle is complete. It is obvious that the inbent ends 5 f f of the wire F, by locking behind the line of stitches K, re-enforce the attachment of the blind to the cheek-strap and make their connection more firm and substantial. As arranged in Figs. 2 and 3, the extreme unfinished 10 edges of both the facings a a' are exposed to view, as seen at a^2 in Fig. 3, this blind being made with quite thick facings for heavy harness; but for lighter harness and when a cheaper blind is required the construction shown in 15 Fig. 4 may be adopted, and wherein the outer facing, a , is to be made of oiled cloth or other suitable light cheap fabric having a proper finish on the outside, and in this case the facing a is bent or turned over for about one-half an inch and pasted on itself, as at a^3 , and 20 around the outside of the wire F, except the loop G, and the inside leather facing, a' , then is pasted to the marginal portions of the facing a , so as to leave a pocket between the facings for the stiffening-plate J, and a row of 25 stitches is made at M around the blind through the outer facing, a , its turned-down edge portion a^3 , and the inner facing, a' , and just inside of the marginal stiffening-wire F and between 30 said wire and the plate J when the latter is put in place. The doubled-over smooth face of the outer facing, a , around the wire F gives a very nice finish to the edge of the blind.

At f f , in dotted lines in Fig. 4, are shown 35 the straight ends of the wire F as they appear before they are turned in behind the row of stitches K in attaching the blind to the cheek-strap B, in the manner above described for the blind shown in Figs. 2 and 3. It is evident 40 that the wire F, having the winker-stay attaching-loop G, need not extend entirely around

the three sides or edges of the blind, as said wire may extend along the top and front edges or but partly around the blind, and so as to properly support the loop G; but the wire F 45 extended entirely around the top, bottom, and front edges of the blind, as above described, is preferred.

In making these blinds all the stitching, whether plain or ornamental, may be finished 50 by machine before the stiffening-plate J is put in place, as will readily be understood.

Having thus described my invention, I claim as new and desire to secure by Letters Patent—

1. A bridle-blind made with a marginal 55 stiffening-wire, F, provided with a projecting loop, G, to receive the winker-stay, and with a stiffening plate, J, pocketed between the facings of the blind and separated from the wire F by a row of stitches, substantially as 60 herein set forth.

2. The combination, in a bridle-blind, of the facings a a' , the marginal wire F, placed between the facings and provided with a projecting loop, G, to receive the winker-stay, 65 and said wire F having ends bent at f f behind the row of stitches K, by which it is attached to the cheek-strap B, substantially as herein set forth.

3. A bridle-blind comprising an outer facing, a , a marginal stiffening-wire, F, having a projecting loop, G, to receive the winker-stay, and said facing a doubled around wire F, as at a^3 , an inner facing, a' , a stiffening-plate, J, 70 pocketed between the facings a a' , and a row of stitches, M, between wire F and plate J, substantially as herein set forth.

EMORY Q. DARR.
